FOREIGN PATENT DOCUMENTS

WO WO 99/25621 5/1999

Primary Examiner — Sheryl Lane

(74) Attorney, Agent, or Firm — Hasse & Nesbitt LLC;
Donald E. Hasse; Daniel F. Nesbitt(57) **CLAIM**

I claim the ornamental design for a box with private label, as shown and described.

DESCRIPTION

FIG. 1 is a perspective view of the new design, with the label removed;

FIG. 2 is a side view of the new design, with the label removed;

FIG. 3 is an end view of the new design, with the label removed;

FIG. 4 is another end view of the new design, with the label removed;

FIG. 5 is a top view of the new design, with the label removed;

FIG. 6 is a bottom view of the new design, with the label removed;

FIG. 7 is a perspective view of the new design, with the label present; and,

FIG. 8 is a perspective view of the new design, with the label removed.

The broken lines show portions of the article and form no part of the claimed design.
